W. E. WINE.
HAND BRAKE MECHANISM.
APPLICATION FILED NOV. 19, 1917.

1,277,803.

Patented Sept. 3, 1918.

INVENTOR

W. Ellings

UNITED STATES PATENT OFFICE.

WILLIAM E. WINE, OF TOLEDO, OHIO, ASSIGNOR TO THE WINE RAILWAY APPLIANCE COMPANY, A CORPORATION OF OHIO.

HAND BRAKE MECHANISM.

1,277,803.

Specification of Letters Patent. Patented Sept. 3, 1918.

Application filed November 19, 1917. Serial No. 202,789.

To all whom it may concern:

Be it known that I, WILLIAM E. WINE, a citizen of the United States, residing at Toledo, in the county of Lucas and the State 5 of Ohio, have invented new and useful Improvements in Hand Brake Mechanisms, of which the following is a specification, reference being had to the accompanying drawings, forming a part thereof.

10 My invention relates to new and useful improvements in hand brake mechanism for railway cars, and has for its object to provide a hand brake which occupies the minimum of clearance space on the end or side 15 of a railway car.

With these and other objects in view, my invention consists of certain improvements, arrangement of parts and combination of elements as hereinafter described and claimed.

20 In the accompanying drawings; Figure 1 is a side elevation showing the application of the device to the side of a flat car; Fig. 2 is a front elevation of same; Fig. 3 is a top plan view of the brake operating device; 25 Fig. 4 is an enlarged section of the brake operating device on line 4—4; Fig. 5 is a section on line 5—5.

Similar characters designate similar parts throughout the several figures of the drawings.

Referring now to the parts by number; the brake operating device 1 (which will be later described) is attached to the top of an angle member 2 which is riveted to the side 35 sill 3 of a flat car near its front right hand corner. Just beneath the side sill 3 is attached a supporting bracket or brake-shaft step 4 which supports the winding drum 5. This winding drum is similar in all respects 40 to that shown in patent granted to me June 9, 1914, bearing Serial Number 1,099,528.

Connecting the brake operating device 1 and winding drum 5 is a square shaft 6 which is socketed in both the winding drum 45 and brake operating device, also immediately beneath the side sill 3 of the car and in close proximity with brake-shaft step 4 is located a sill step 7.

On the left hand side of the angle member 2 is shown located a hand hold or grab iron 8 to which the trainman may hold while operating the brakes.

It will be noted that handle 9 can be oper-

ated in a number of positions from 9^a to 9^d. When the trainman is standing on the sill 55 step 7, the handle 9 can be easily operated from position 9^a to 9^b. This position is the only one available for operating the brakes when the car is loaded, but when there is sufficient room on the car for standing 60 thereon, the handle can be operated from position 9^c to 9^d. Should the handle 9^a slip from the trainman's hand, the lug 10 on the inner face of the handle 9 will strike lug 11 and immediately disengage the handle. 65

Referring now specifically to the construction of the brake operating device, the bevel gears 12 and 13 are suitably mounted in a housing 14 and compactly held therein. The bevel gear 12 is provided with a hub 70 15 which is journaled in a bearing 16 in the bottom of housing 14. The bevel gear 13 is provided on its outer periphery, and integral therewith, with teeth 17 forming a ratchet. The bevel gear 13 is also provided with a 75 long hub portion 18 on one side thereof which is journaled horizontally in a bearing 19 in a housing 14.

On the outer face of the bevel gear 13 is a hub 20 to which is slidably connected the 80 handle 9. The upper end of handle 9 is provided with a slot 21 in which the hub 20 is free to rotate, and oscillate longitudinally of the handle. On the inner face of the handle 9 is located the lug 10 which is 85 adapted to engage teeth 17 of the ratchet while the handle is moved radially upward but so formed that it will immediately release when the handle is freed by the operator. 90

The housing 14 is provided with a vertical extension 22 to which is pivoted the pawl 23 for engagement with the teeth 17 of the ratchet, the pawl 23 being held in engagement with the housing by means of bolt 24. 95 The hub 15 of bevel gear 12 is held in its bearing by means of cap 25 and pin 26. Combination bevel and ratchet 13 is held in its operative position with hub 18 engaging bearing 19 and hub 20 engaging the upper end of the handle 9 by means of bolt 28, the length of hubs 18 and 20 being slightly greater than the engaging members so that when the bolt 28 is drawn up perfectly tight, the bevel gear 13 is perfectly free to rotate. 100 The housing 14 is provided also with two 105

rearwardly extending ribs 27 forming attaching means for the device.

While the device is here shown applied to a flat car, it is applicable with no change in construction whatever of the device to practically all classes of freight equipment and particularly adapted to gondola and hopper cars.

It will therefore be seen that this device 10 is very simple in its construction and can be very easily repaired. By removing the nut from end of bolt 28, the handle 9 and bevel gear 13 can be removed without any obstruction whatever. Then if it is desired 15 to remove bevel gear 12, the cap 25 and pin 26 can be removed leaving the housing 14 and all the other parts of the brake operating mechanism in position on the car.

It will therefore be understood that from 20 the ease with which these parts can be removed, that repairs to same can be very easily made and with considerable despatch.

It will be understood from this description that although the improvements in this 25 invention are simple, they accomplish in a thoroughly practical manner all the objects sought.

I wish it further understood that I do not 30 desire to be limited to the specific construction or arrangement of elements shown and described, as it is obvious that changes in construction and arrangement may be made without departing from the spirit of the invention.

Having thus described my invention, I 35 aim in the appended claims to cover all modifications which do not involve a departure from its spirit and scope.

What I claim as new and desire to secure by Letters Patent of the United States is: 40

1. In a hand brake mechanism, a housing, bevel gears within the housing, bearings in the housing for said bevel gears, a ratchet wheel connected to one of the gears and a handle radially movable into engagement with said ratchet wheel for operating the brakes.

2. In a hand brake mechanism, a housing, bevel gears within the housing, bearings in the housing for said gears, a ratchet wheel 50 connected with one of said gears, a hub member extending outwardly from said ratchet wheel, a handle engaging said hub member, a lug on the handle radially movable into engagement with the ratchet wheel, and a bolt extending through the housing, ratchet wheel and handle for retaining the parts in operative position.

3. In a hand brake mechanism, a housing, bevel gears in the housing, said housing provided with bearings for said bevel gears, a ratchet wheel connected to one of said gears, a handle pivoted concentrically with said ratchet wheel and provided with a lug radially movable into engagement with teeth on said ratchet wheel and a lug on the housing adapted to engage a portion of the handle to forcibly disengage the handle from the ratchet wheel.

This specification signed and witnessed 70 this 17th day of November 1917.

W. E. WINE.
